Primary Examiner — Rosemary K Tarcza*Assistant Examiner* — James Thorn, Sr.(74) *Attorney, Agent, or Firm* — Fattibene and Fattibene LLC; Paul A. Fattibene(57) **CLAIM**

The ornamental design for a vegetable retainer for vegetable cooking utensil, as shown and described.

DESCRIPTION

FIG. 1 is a front elevation view a vegetable retainer for vegetable cooking utensil showing the new design;

FIG. 2 is a rear elevation view thereof;

FIG. 3 is a top plan thereof;

FIG. 4 is a bottom plan view thereof;

FIG. 5 is a left side elevation view thereof;

FIG. 6 is a right side elevation view thereof;

FIG. 7 is a top perspective view thereof;

FIG. 8 is a bottom perspective view thereof; and,

FIG. 9 is an enlarged bottom perspective view thereof.

The broken lines shown are for illustrative purposes only and from no part of the claimed design.
